United States Patent Office

Des. 201,966
Patented Aug. 17, 1965

201,966

WALL BLOCK UNIT

Verne Frese, 7265 E. Marginal Way, Seattle, Wash.

Filed Sept. 19, 1963, Ser. No. 76,647

Term of patent 14 years

(Cl. D18—2)

FIG. 1

FIG. 2

FIG. 3

FIG. 4

FIG. 1 is a front elevational view of a wall block unit showing my new design,

FIG. 2 is an end view as seen from the left of FIG. 1, FIG. 3 is a top plan view of the wall block unit; and FIG. 4 is a front perspective view thereof.

The dominant features of my design reside in the portions shown in full line.

I claim:

The ornamental design for a wall block unit, as shown and described.
